UNITED STATES PATENT OFFICE.

JAMES F. McCURDY, OF SAN JOSE, CALIFORNIA.

TRY-SQUARE.

No. 883,041.

Specification of Letters Patent.

Patented March 24, 1908.

Application filed June 28, 1906, Serial No. 323,808. Renewed September 6, 1907. Serial No. 391,700.

To all whom it may concern:

Be it known that I, JAMES F. McCURDY, a citizen of the United States, residing at San Jose, in the county of Santa Clara and State of California, have invented new and useful Improvements in Try-Squares, of which the following is a specification.

The invention relates to an improvement in try squares, comprehending specifically a means whereby the square may be readily adjusted for serving as a miter or bevel square.

The main object of the present invention is the production of a try square provided with an adjustable member adapted when in normal position to form a part of the square stock, and attached to be adjusted to provide a particular angle of inclination relative to the edge of the blade of the square, thereby rendering the ordinary try square adjustable to form a bevel or try square.

The invention will be described in the following specification, reference being had particularly to the accompanying drawings in which:

Figure 1 is a view in elevation of a try square provided with my improvement, Fig. 2 is a rear elevation of the same, Fig. 3 is a view similar to Fig. 1 showing the device adjusted for use as a bevel square, Fig. 4 is an end elevation of the try square with the attachment shown in normal position, Fig. 5 is a section on line 5—5 of Fig. 1.

Referring to the drawings, wherein similar reference numerals indicate like parts throughout the several views, the try square proper is of ordinary form comprising a stock 1 to which is secured the blade 2, the latter being preferably graduated along one edge in inches and fractions thereof, as at 3, all of which parts are of the usual or any preferred construction.

The improved attachment comprises an arm 4 coextensive in length and thickness with the stock 1, but of materially less width. The arm 4 is formed with a centrally disposed longitudinally arranged slot 5 extending the greater portion of the length thereof and of a width to receive the blade 2. The slot 5 opens through the relatively inner or pivoted end of the arm, dividing the arm into practically two sections for the greater portion of its length, which sections are designed to embrace the blade 2 of the square, as shown in Fig. 4. Each of the sections of the arm at

the free end is formed with an extension 6, having a free relatively rear face or edge 7 curved concentric to the pivot pin 8 of the arm, as clearly shown in the drawings. Each of the extensions 6 is seated in a correspondingly recessed portion 9 of the stock, the wall of the recess 9 and the curved face 7 of the extension serving to accurately guide the arm in movement. The pivotal connection of the arm is preferably disposed near the gage edge of the blade, and the length of the slot 5 is such as to permit independent movement of the arm without obstruction from the edge of the blade. A guiding strip 10 is secured to the arm near the free end of the latter, being preferably curved concentric to the plane of movement of the arm and being guided in operation in an appropriately shaped guideway 11 formed transversely of the stock 1. A binding screw 12, operatively engaging a wear plate 13 secured in the stock, is designed to coöperate with the guide strip 10 and engage the latter to secure the arm 4 in adjusted position relative to the blade.

One face of the blade 2 is preferably provided with a series of indicating lines 14, forming the usual lines of bevel in cutting rafters or the like, while the opposite face of the blade is formed with a second series of indicating lines 15 marked to indicate degrees of angle relative to the operative edge of the blade, providing the ordinary miter line.

The face or free edge of the arm 4 is, of course, designed to provide a true right angle with the operative edge or edges of the blade 2, so that when the arm is in normal position, as shown in Fig. 1, the device as a whole forms the usual try square, being adapted for all purposes for which such an article is designed. When, however, it is desired to adjust the device to provide a bevel or miter square the binding screw 12 is loosened and the arm 4 turned on its pivot 8 until the forward or bearing face thereof registers with the one of the particular indicating line desired. The said binding screw is tightened to engage the guide strip and secure the arm in such adjusted position, whereupon said arm forms in effect the stock of the square with which the operative edge of the blade forms a definite angular relation. As the arm 4 is arranged on both sides of the blade it is apparent that the registration of the operative face of the arm with either the

bevel or miter indicating lines is readily accomplished with accuracy. The co-operation of the curved face of the extension 6 with the wall of the recess 9 in the stock provides for accurately guiding the arm in operation, thereby insuring and maintaining a fixed definite relation of the plane of operation of the arm and stock.

The attachment is simple and, as will be obvious is readily applicable to try squares now in use, and when so attached materially increases the efficiency of the try square in combining therewith a bevel and miter square. Furthermore, as the arm 4 is the effective gaging surface in the use of the device as a try square, bevel square or miter square the particular angular relation of the ordinary stock with the blade is not material, thereby dispensing with the care in construction heretofore necessary in insuring a true right angle between the face of the stock and the edge of the blade, as the adjustment of the arm 4 will insure such angular relation at will.

Having thus described the invention what is claimed as new, is:—

A try square including a stock and a fixed blade projecting therefrom, an arm pivotally secured to the blade on opposite sides thereof, a guiding strip projecting from the arm adjacent its free edge and operative through an opening formed in the stock, means to secure the strip in adjusted relation, and extensions projecting from the arm adjacent the pivoted end thereof, said extensions seating in recesses formed in the stock of a depth corresponding to the thickness of the extension, one wall of the recess and the contacting wall of the extension being curved concentric with the pivot point of the blade, whereby said walls are in engagement during full movement of the arm to guide the arm.

In testimony whereof, I affix my signature in presence of two witnesses.

JAMES F. McCURDY.
